BABY'S WALKER

Harry R. Hall, Youngstown, Ohio

Filed July 21, 1960, Ser. No. 61,460

Term of patent 14 years

(Cl. D15—1)

Figure 1 is a top plan view of a baby's walker showing my design;

Figure 2 is a perspective view of an enlarged scale; and Figure 3 is a side elevational view thereof.

I claim:

The ornamental design for a baby's walker, as shown.
